GAME BOARD

Frank K. Maitland, Hermosa Beach, Calif., assignor to J. Frank Meyer, Flintridge, Calif.

Application May 29, 1934, Serial No. 728,073

3 Claims. (Cl. 273—121)

My invention relates to game boards, and has particular reference to game boards employing counters which may be distributed in various positions upon the board, the positions designating 5 predetermined values.

Game boards employing a number of pockets, holes or other play-piece receptacles, distributed thereover to receive playing pieces projected upon the board, are well known, the most common form thereof being known as the "pin and marble" games, comprising, essentially, a playing board provided with a plurality of holes for the reception therein of balls which are projected upon the playing field by any suitable projecting devices. These boards are usually supported at a considerable angle to the horizontal so that the ball once projected upon the board will travel by gravity over the board, striking the pins or other obstructions disposed over the 10 surface of the board to direct the balls into the various pockets thereon. Each of the pockets is usually designated with a predetermined scoring value so that those pockets in which it is most difficult to place the balls, have the 15 higher scoring values.

To add further attractiveness to the game, various devices for advancing the scoring values are sometimes provided, and it is an object of my invention to provide a new and novel device for 20 advancing the scoring values of the playing pieces or balls which are projected upon the game board.

Another object of this invention is to provide a game board in which a portion of the board is provided with a plurality of pockets and is separated from the remaining portions of the board so that balls placed in the separated section of the board may be advanced in values by movement of the separated section of the board.

Another object of the invention is to provide a game board as set forth in the preceding paragraph, in which a predetermined pocket on the remaining portion of the board is adapted to 45 receive a ball therein to operate mechanism for causing the separated section of the board to advance the value of balls therein.

Another object of the invention is to provide a simple operating mechanism for moving the separated section of the board to advance the value of the balls therein.

Another object of the invention is to provide a new and novel elevating mechanism which may be employed for lifting balls which have been 50 played upon the board back to a position in front

of projecting devices employed for projecting the balls over the board.

Other objects and advantages will be apparent from, and best understood by reference to, the following specifications read in connection with 5 the accompanying drawings, wherein

Figure 1 is a top plan view of the game board constructed in accordance with my invention;

Fig. 2 is a detail diagrammatic view of the separated section of board constructed in accordance with my invention, and illustrating the control and operating mechanism therefor;

Fig. 3 is a detail vertical sectional view of a portion of the board, taken along lines III—III of Figs. 1 and 5;

Fig. 4 is a detail plan view of a portion of the board, illustrating the ball-releasing mechanism employed in connection with my invention;

Fig. 5 is a vertical sectional view, taken along line V—V of Fig. 3;

Fig. 6 is a detail, horizontal sectional view of one end of a game board constructed in accordance with my invention and illustrating particularly the ball-elevating mechanism of my invention;

Fig. 7 is a detail, vertical sectional view, taken along line VII—VII of Fig. 6;

Fig. 8 is a vertical sectional view, taken along line VIII—VIII of Fig. 6; and

Fig. 9 is a detail, sectional view, taken along line IX—IX of Fig. 5.

Referring to the drawings, I have illustrated, in Fig. 1, a game board apparatus constructed in accordance with my invention, as comprising a suitable, substantially rectangular cabinet 1, the top of which is adapted to be enclosed by means of a top 2 constructed of glass or other transparent material, which will permit a view of the playing board 3 therethrough. The playing board is illustrated as comprising an elongated rectangular board extending from the rear end 4 of the cabinet to a point spaced slightly inwardly of the front end 5 of the cabinet.

As will be understood by those skilled in the art, the board 3 forms a main playing field over which play pieces, such as balls, may be projected and is provided with a suitable border construction 6 comprising a substantially curved surface at the rear end of the board and providing relative narrow marginal portions 7 and 8 extending along the extreme sides of the playing field to assist in the guiding of balls over the playing field. A portion of the border member 6 is illustrated as comprising a relatively thin wall 9 which extends along the right-hand side of the

playing field but substantially inwardly a short distance from the extreme outer side boundary 1 thereof to constitute therebetween a channel 10 through which balls may be projected by means 5 of suitable spring projecting mechanism 11 located at the front right-hand side of the cabinet.

The playing surface of the playing board 3 is provided with a number of holes 12 extending therethrough to constitute play-piece receptacles 10 or ball-receiving pockets distributed in any desired pattern throughout the board. Each of the holes 12 is designated with a predetermined scoring value, dependent upon the difficulty of placing a ball in the particular pocket. To increase 15 the skill required to place balls into the various pockets, I provide pins 13, or other obstructing devices, which will be encountered by the balls, causing them to bound from the pins or obstructions in various directions as the balls pass down- 20 wardly over the playing field 3.

It will be understood by those skilled in the art that the end of the playing field 3, adjacent the rear end 4 of the cabinet, will be at a considerably higher elevation than that portion of the playing 25 board near the front end 5 of the cabinet, so that the balls once projected upon the field will tend to move by gravity downwardly over the field, traversing various paths, determined by the pins which may be encountered by the ball during its 30 passage over the playing field.

As will be understood by those skilled in the art, a secondary board 14 is mounted immediately below the playing board 3, provided with a plurality of holes 15 distributed in exactly the same 35 pattern as the pattern of the holes 12 in the playing board 3 but the secondary board is preferably shorter than the playing board 3 so that when the same is in its normal position, as illustrated in Fig. 1, the holes 15 thereof are spaced 40 slightly out of alignment with the holes 12 on the playing field 3. The secondary board is slidably mounted for movement longitudinally of the cabinet 5 and may be moved toward the rear wall 4 of the cabinet by means of suitable coin-controlled mechanism illustrated at 16, the secondary board 14 being normally urged to return to its normal position shown in Fig. 1 by means of a suitable spring 17.

It will also be understood by those skilled in the 50 art that when the secondary board 14 is in its normal position, as illustrated in Fig. 1, the holes 12 will constitute pockets or ball-receiving depressions, permitting the balls to be seated therein, resting upon the secondary board 14, but when 55 the secondary board 14 is moved rearwardly by the coin-control mechanism 16 the holes 15 in the secondary board 14 will be aligned with the holes 12 and will allow the balls to drop through the aligned holes to a sub-floor 18, shown particularly in Fig. 3.

The sub-floor 18, like the playing board 3 and the secondary board 14, extends at a considerable angle to the horizontal to insure that the balls which drop onto the floor 18 will move toward 65 the front end of the cabinet 5, ready to be passed to the projector 11, as will be more fully described hereinafter.

The game may be considerably enhanced by 70 providing mechanism which will advance the score of balls placed in certain of the pockets upon the projection of another ball into a selected other pocket. I have shown such mechanism as indicated particularly in Figs. 3 and 4, at 75 20. The cut-out portion of the playing board 3 may be of any desired shape, to be filled with a

separate playing field section 21 placed in substantial alignment with the plane of the surface of the playing board 3.

In the form of the apparatus disclosed herein, I have illustrated the cut-out portion 20 as being in the form of a circle, to be closed by a circular disc-like member forming the separate playing field section 21. The separate section 21 is provided with a plurality of pockets 22 distributed in any desired pattern over such section to receive 10 balls therein. The primary characteristic of the separate section 21 of the board is that the balls, when placed in the pockets, may be advanced to additional scoring values by movement of the pocket or ball-receiving members 22. 15

In the form of the apparatus shown herein, the separate section or disc 21 has the pockets 22 distributed therearound in the form of a circle and the separate section 21 is mounted upon a suitable vertical pivot 23 about which it may rotate so that when a ball is placed in one of the pockets, the entire section with its pockets may be advanced from its initial position to a second position, giving that ball in that pocket a higher scoring value. 20

By referring particularly to Fig. 1 it will be observed that suitable guide bars 24 and pins 25 are associated with the board 3 directly in advance of the separate section 21 of the board so as to guide balls into that pocket 22 which is 30 nearest the rear end of the board. Thus by causing rotation of the disc 21 the ball which has been placed in the rearmost pocket, will be moved with its pocket to place the ball and pocket to a new position having a higher scoring value 35 and to move the next pocket 22 to the rearmost position, ready to receive a second ball guided therein by the pins 25 and guide bars 24. 25

By referring particularly to Figs. 2, 3, 4 and 5, it will be observed that the separate section 21 of the board is rigidly mounted upon the upper end of a shaft 23, which shaft is secured, to the hub of a disc 26 arranged to be rotated by any suitable power mechanism. A simple form of power mechanism is illustrated herein as comprising the structure of an ordinary vibrating electric bell 27, the vibrator or clapper 28 of which is connected by means of a link 29 to a lever 30 preferably pivoted as at 31 to the shaft 23. The lever 30 is normally urged in a clockwise direction by means of a spring 32 and is drawn in a counter-clockwise direction by the energization of the coils 33 of the electric bell 27. The lever 30 is provided with a dog 34 which is pivoted upon the lever as at 35, the dog extending toward 50 and into contact with the disc 26, engaging the disc at a considerable angle to the radius of the disc 26. The dog 34 is normally urged toward the disc 26 by means of a suitable spring 37 so that when the lever 30 is moved in a clockwise direction the dog 34 will grip the disc and move the same a similar distance in a clockwise direction, while, when the coils 33 of the electric bell 27 are energized to draw the lever 30 in a counter-clockwise direction, the dog 34 will slip along the 55 disc 26 to obtain a new grip ready to move the disc forwardly again upon the next clockwise movement of the lever 30. The bell-clapper 28 of the bell 27 will also strike the bell, the audible alarm of which gives the player an audible signal 60 of his success in advancing the ball on the auxiliary playing-field.

By referring particularly to Figs. 1 and 2, it will be observed that one of the holes 12, which is indicated by the reference character 12A, may 75

be selected as the particular pocket in which a ball may be placed to cause the operation of the electric bell 27 to cause movement of the separate section 21 of the game board.

The secondary board 14 preferably does not extend under the pocket 12A so that a ball placed in this pocket will immediately pass through the pocket 12A to the sub-floor 18. However, an electrical contact mechanism may be interposed between the playing board 3 and the sub-floor 18, which I have illustrated at 38. This electrical contact mechanism may be selected of any suitable size, shape or form, so that a ball dropping through the pocket 12A will close an electric circuit for the ball.

In the form of the device illustrated herein, the electric contact mechanism 38 consists of a trough pivoted at 39 upon a suitable bearing member 40 secured to the sub-floor 18. The outer end 41 of the trough 38 is provided with an arm 42 arranged to engage and close a pair of electrical contacts 43 which will complete a circuit, as shown in Fig. 2, extending from an electric battery 45 (preferably a number of dry cells contained within the cabinet) by way of conductor 46, contacts 43, conductors 47 and 48, terminal 49 of the electric bell 27, and thus from the opposite terminal 50 of the electrical bell 27 by way of conductor 51 to the opposite terminal of the battery 45.

It will be apparent that the dropping of the ball upon the trough 38 will close the contacts 43 momentarily and to insure that the electric bell 27 will remain energized a sufficient length of time to advance the separate section 21 of the playing board to its next position, I provide the disc 26 with a plurality of holes 52 so distributed around the disc with relation to the location of the pockets 22 in the separate section 21 that one of these holes 52 is presented immediately above the operating lever 53 of a secondary switch.

As is particularly in Fig. 9, the operating lever 53 consists of a bellcrank pivoted as at 55 to a bearing member 56 mounted upon the main floor 58 constituting the bottom of the cabinet 1, the longer arm of which is baffled as indicated at 59 in the direction of movement of the disc 26, while the shorter arm of the lever 53 is arranged in abutting relation with a spring contact 60 which may be moved into contact with a stationary contact 61 forming the contacts of the secondary switch.

It will, therefore, be apparent that while a momentary closing of contacts 43 will start the electric bell 27 to start the movement of the disc 26 and the separate section 21 of the game board, the initial movement of the disc 26 will depress the lever 53 to close the contacts 60, 61 and maintain these contacts closed until the next hole 52 in the disc 26 arrives immediately above the long arm of the lever 53 at which time the lever 53 will be pressed upwardly by the spring contacts 60, permitting the spring contact 60 to move out of contacting relation with its stationary contact 61. This will maintain the circuit to the electric bell completed until the separate section 21 of the board has completed its movement to its next position.

It will be observed that the contacts 60, 61 are connected by means of conductors 62 and 63, respectively, to conductors 46 and 47, thus connecting the secondary switch contacts 60, 61 in parallel relation with the contacts 43.

With a game board constructed as thus far de-

scribed, it will be apparent that by projecting a ball onto the playing field 3 in such manner as to cause the ball to enter the rearmost pocket 22 on the separate section 21, and then projecting another ball so as to fall into the pocket 12A, that ball which has been received in the separate section 21 will be moved to the next position, while another pocket 22 of the separate section 21 will be placed in the rearmost position for the reception of another ball. This may be repeated, depending upon the skill of the person playing the game, until all of the pockets are filled and until the first ball placed in the first of the pockets 22 has been moved to a position of highest scoring value.

In order to prevent the balls from passing directly through the holes or pockets 22, I provide a secondary plate 64 located below the separate section 21, and preferably mounted for rotation upon the shaft 23. The secondary plate 64 has a plurality of holes 65 formed therein, corresponding in location with the location of the holes or pockets 22 in the separate section 21, but normally the secondary plate 64 is held in a position such as to displace the holes 65 out of alignment with the holes 22 of the separate section 21.

When the game is completed and it is desired to allow all of the balls to fall upon the sub-floor 18 for assembly to re-play the same, the forward movement of the secondary board 14 may be employed to cause a movement of the secondary plate 64 relative to the separate section 21, to align the holes 65 with the holes 22 and allow the balls to pass therethrough. This may be arranged by providing a suitable spring 66 interconnecting the secondary plate 64 with the separate section 21 and normally urging this plate to its normal position, as shown in Fig. 2, at which time a pair of stop members 67, mounted respectively upon the separate section 21 and the secondary plate 64, are in engagement with each other. The movable secondary board 14 may be provided with a pawl 68 aligned with a plurality of notches 69 in the outer periphery of the secondary plate 64, so that rearward movement of the secondary board 14 will cause the pawl 68 to engage one of the notches 69 and move the secondary plate 64 in a counter-clockwise direction.

It will be observed that at this time the separate section 21 of the board is prevented from counterclockwise movement by reason of the engagement of the dog 34 of the lever 30 so that the separate section 21 is held stationary during the counterclockwise movement of the secondary plate 64. If desired, the pawl 68 may be pivoted to the secondary board 14, as indicated at 70, to permit the pawl to follow with the circular path of travel of the plate 64. In such case the pawl 68 should be urged to its normal position by means of a suitable spring 71, the pawl 68 being stopped in its normal position by means of a suitable stop plate 72.

In order to facilitate the assembly of the board, I prefer to mount the separate section 21 and the secondary plate 64 upon the shaft 23 which is, as shown in Fig. 5, of tubular construction, thus permitting the entire assembly to be removed as a unit, the tubular shaft 23 being assembled with the disc 26 as by means of a pin 73 extending upwardly from the disc 26 and having a spline 74 thereon for connection with a corresponding spline on the lower end of the tubular shaft 23.

By referring particularly to Figs. 6, 7 and 8, it will be understood by those skilled in the art that when the balls have been played upon the board 75

3, and have been released by rearward movement of the secondary board 14, the balls falling upon the sub-floor 18 will move toward the forward end 5 of the cabinet 1 where these balls will come to rest in a suitable trough 75 preferably extending as shown in Fig. 7 at an angle to the horizontal to direct the balls toward the right-hand side of the cabinet 1.

It will be observed, however, that the level of the sub-floor 18 is considerably lower than the level of the playing board 3, and in order to restore the balls to the playing level it is necessary to provide a ball-elevating mechanism. A simple form of ball-elevating mechanism is shown herein as comprising a sector 76 pivoted as at 77 to the right-hand side wall of the cabinet 1. The sector 76 projects through a suitable slot 78 in the trough 75 to engage the ball 79 lying closest to the right-hand wall of the cabinet 1 at a point slightly to the left of the center of the ball 79. Thus by swinging the sector 76 about its pivot 77 the ball 79 will be lifted by the edge of the sector 76 in a vertical direction until it becomes level with a recess 80 constituting an extension of the channel 10.

It is usual to provide a partition wall 81 in the forward end of the cabinet 1, and this wall may constitute one of the walls of the trough 75 so that the ball will be guided by the partition 81 in a vertical direction. The recess 80 is illustrated in Fig. 7 as having its lower surface inclined slightly toward the right-hand side of the cabinet 1 so that once the balls have been lifted up to the recess 80 they will move into the recess and remain therein even though the sector 76 is retracted to its normal position as shown in Fig. 8.

The sector may be operated in any suitable manner, though I prefer to provide a plunger 82 extending through the lower end 5 and arranged to be pressed inwardly by the person playing the game, the inner end of the plunger 82 engaging one edge of the sector 76 so that inward movement of the plunger will cause the sector 76 to be rotated to lift the balls one by one into the recess 80. A suitable spring 83 may be provided to normally hold the sector 76 in its retracted position, as shown in Fig. 8.

While I have shown and described the preferred embodiment of my invention, I do not desire to be limited to any of the details of construction shown herein, except as defined in the appended claims.

I claim:

1. In a game board, means defining a main playing field having a plurality of play piece receptacles distributed thereover, means defining a playing field section separate from said main playing field and having a play piece receptacle

thereon, means mounting said auxiliary playing field for movement relative to said main playing field to move play pieces on said auxiliary playing field to different positions relative to said main playing field, electrical vibratory means connected to said auxiliary playing field to move said playing field, a circuit for said electrical vibratory means, and additional contact means operably responsive to the initial movement of said playing field for maintaining said circuit closed until said playing field has moved to a predetermined position.

2. In a game apparatus, a cabinet including a member providing a playing surface provided with a cut-out portion and having a ball-receiving pocket formed therein; a member rotatably mounted in said cut-out portion and having a ball-receiving pocket formed therein; means for propelling balls one at a time over said playing surface so that they may enter into one of said pockets; a member rotatably mounted in said cabinet below said playing surface for temporarily retaining therein a ball which enters into the said second-named ball-receiving pocket formed in said rotatable member; means including a device actuated by a ball entering said first-named ball-receiving pocket for moving said rotatable member and a ball disposed in the said ball-receiving pocket formed therein a predetermined circumferential distance relative to said playing surface; and means including a member slidably mounted in said cabinet below said playing surface for moving said ball-retaining member so as to release a ball held thereby in the said second-named ball-receiving pocket.

3. In a game apparatus, a cabinet including a member providing a playing surface provided with a cut-out portion and having a ball-receiving pocket formed therein; a member rotatably mounted in said cut-out portion and having an annular row of ball-receiving pockets formed therein; means for propelling balls one at a time over said playing surface so that they may enter into one of said pockets; a member rotatably mounted in said cabinet below said playing surface for temporarily retaining therein a ball which enters into one of the said ball-receiving pockets formed in said rotatable member; means including a device actuated by a ball entering said first-named ball-receiving pocket for moving said rotatable member and a ball disposed in one of the said ball-receiving pockets formed therein a predetermined circumferential distance relative to said playing surface; and means including a member slidably mounted in said cabinet below said playing surface for moving said ball-retaining member so as to release balls held thereby in the said second-named ball-receiving pockets.

FRANK K. MAITLAND.
